UNITED STATES PATENT OFFICE

2,425,633

STOKER APPARATUS

Donald J. Mossart, Ardmore, Pa., assignor to
Westinghouse Electric Corporation, East Pitts-
burgh, Pa., a corporation of Pennsylvania

Original application July 29, 1942, Serial No.
452,759. Divided and this application June
30, 1945, Serial No. 602,493

1 Claim. (Cl. 122—376)

1

This invention relates to fluid-cooled stokers, more particularly to multiple-retort underfeed stokers, and it has for an object to provide improved apparatus of this character.

This and other objects are effected by the invention as will be apparent from the following description and claim taken in connection with the accompanying drawings, forming a part of this application, in which:

Fig. 1 is a perspective view of a multiple-retort underfeed stoker embodying the present invention, portions of the apparatus being omitted in order to more clearly disclose features of the invention;

Fig. 2 is a side elevational view, partially in section, of a stoker tuyère row together with the cooling system therefor and various associated parts;

Fig. 3 is a side elevational view of a tuyère side wall row, with portions thereof broken away for the sake of clearness; and,

Figs. 4, 5 and 6 are transverse sectional views taken along the lines IV—IV, V—V and VI—VI, respectively, of Fig. 3, looking in the direction indicated by the arrows.

Referring now to the drawings more in detail, there is shown, at 10, a fluid-cooled stoker embodying the present invention and comprising alternately arranged retorts 11 and tuyère rows 12, together with side wall tuyère rows 13. Fuel is fed to the retorts 11 through the ram openings 14 of the upper ends of the retorts and is advanced along the latter to the rear of the stoker by means of secondary rams 16, which, as herein illustrated, are of conventional construction and form no part of the present invention. Air-distributing box structure 17 is provided at the upper ends of the retorts 11 and the tuyère rows 12, for supplying secondary air to the combustion chamber in the usual manner.

Each tuyère row 12 comprises a plurality of composite tuyère center members 20 arranged in end-to-end relation, each such member comprising a tuyère nose portion 21 and a plurality of separate tuyère side members 22 adapted to cooperate therewith to provide substantially horizontal fuel-supporting surfaces arranged in stepped relation. Each of the tuyère center members 20 is provided in its under surface with a groove (not shown) adapted to closely receive and be supported by a cooling-fluid tube 23 positioned therebelow and extending lengthwise of the tuyère row from the upper to the lower end thereof. The specific construction and arrangement of the tuyère row construction forms no part

5 of the present invention herein disclosed and claimed but is fully disclosed in detail in applicant's copending application, Serial No. 452,759, filed July 29, 1942, now Patent Number 2,402,906 patented June 25, 1946, the present application being a division of this earlier filed copending application.

10 As best illustrated in Fig. 2, the tube 23 has its terminal portions threadedly connected to and supported by upper and lower hollow end castings 25 and 26, respectively, at opposite ends of the tuyère row. Cooling fluid, for example water, is supplied to the lower end casting 26 from the header 27, for passage through the tube 23, by means of the connecting supply pipes 28 and 29. The cooling fluid, upon leaving the tube by way of the hollow casting 25, is conducted to a heat exchanger 30 by connecting pipes 32, 33 and 34. After giving up a predetermined quantity of heat in the heat exchanger, the cooled water is returned to the supply header 27 by way of the return pipes 35, 36, 37 and 38.

15 While the cooling system herein disclosed is independent of the boiler water system and involves the use of an independent heat exchanger, it will be apparent to those skilled in the art that the invention is not limited to the use of such a system but may well include other arrangements, for example, passing boiler water through the tubes 23. The closed cooling system with the independent heat exchanger, herein illustrated, forms no part of the present invention, the latter being concerned with the side wall tuyère rows 13.

20 Referring now to Figs. 3, 4, 5 and 6, there are provided flanged structural supporting members 50 and 51, providing therebetween an air space 52 communicating with the plenum chamber 53, therebelow (Fig. 2). An angle support member 54 has a bottom flange 55 resting upon the supporting members 50 and 51 and provided with openings 56 therethrough for flow of air from the plenum chamber. The angle support includes an inclined inner wall construction formed by spaced ribs 57 providing openings 58 therebetween, the outer surfaces of the ribs being concaved to provide cradle structures 59 for the reception of a longitudinally-extending cooling tube 61. This tube has its terminal portions threadedly mounted in and supported by an upper end casting 62 and a lower end casting 63, cooling fluid being supplied to the latter from the main supply header 27 by the connecting pipes 64 and 65 for flow through the tube (Fig. 2). After passage through the tube 61, the cooling fluid is conducted from 25 the hollow upper end casting 62 to the heat ex-

changer 30 through the discharge pipes 67 and 68.

The upper and lower end castings are substantially identical and reference is made to Fig. 4, which is a sectional view through the upper end casting, for a description of the construction of both. The casting is provided with an inner face plate 69 having a plurality of perforations 70 extending therethrough for passage of air from the plenum chamber to the fuel bed adjacent the face plate 69. The plate has depending lugs 72 at its upper edge and similar lugs 73 at its lower edge, the former being adapted to extend behind the upper edge of the angle support 53a and the lower lug hooking inside the flanged edge of the supporting member 51. The space between the angle support 53a and the furnace side wall 74 preferably is packed with suitable material 75, the latter being supported from beneath by the strip 76.

Between the upper and lower end castings, the tube 23 is covered by face plates 78 (Figs. 5 and 6) having perforations 79 therethrough for passage of air for combustion purposes. The face plates are provided on their sides adjacent the tube with parallel spaced ribs 80 having formed therebetween a concave trough 81 adapted to closely fit the tube 61 in heat-transfer relation thereto. A lug 82 depends from the upper edge of each plate and projects downwardly outside of the angle support 53, the space between the angle support and the furnace side wall 74 being filled with packing 75 retained by the supporting strip 76, as in the vicinity of the upper and lower end castings.

A plurality of bolts 83 serve to retain the face plate 78 in position with respect to the angle sup-

port 53, with the tube 61 clamped therebetween. Nuts 84, positioned in recessed slots 85 of the angle support 53, are threaded upon the bolts 83.

While the invention has been shown in but one form, it will be obvious to those skilled in the art that it is not so limited, but is susceptible of various changes and modifications without departing from the spirit thereof.

What is claimed is:

10. In a stoker for furnaces, the combination of spaced support members defining a furnace side wall air box adapted to receive air under pressure, a back support member resting upon said spaced support members and bridging the space therebetween, said back support member providing for flow of air therewith from said air box and having a tube-receiving groove in one side surface, a side tuyère plate having a tube-receiving groove in one surface opposed to the tube-receiving groove of the back support member, a fluid-conducting tube disposed partially in each of said tube-receiving grooves, and means for securing said tuyère plate to said back support member with said tube clamped therebetween, said tuyère side plate having lateral passages therethrough for flow of air from the furnace side wall air box to the interior of the furnace.

DONALD J. MOSSHART.
